UNITED STATES PATENT OFFICE.

GEORGE H. TOWNSEND, OF MADISON, WISCONSIN.

KNOCKDOWN BOX.

1,317,836.

Specification of Letters Patent.

Patented Oct. 7, 1919.

Application filed March 8, 1915. Serial No. 12,714.

To all whom it may concern:

Be it known that I, GEORGE H. TOWNSEND, a citizen of the United States, residing at Madison, in the county of Dane and State 5 of Wisconsin, have invented certain new and useful Improvements in Knockdown Boxes, of which the following is a specification.

My invention relates to a knock down box and may be applied to shipping cases and 10 crates in general. The object of my invention is to provide a shipping case inexpensive to make that can be quickly collapsed and set up and strong enough to carry heavy 15 shipments and suitable to be used again and again for shipping purposes. I attain these results by a construction illustrated in the accompanying drawing in which—

Figure 1 is a top view.

Fig. 2 is a side elevation.

20 Fig. 3 is an end elevation.

Fig. 4 is a top view with the slotted fastener removed and retaining cleat indicated.

Fig. 5 is an end view of the top member on edge.

25 Fig. 6 is a top view of slotted fastener for mounting on transverse bars of top and bottom members.

Fig. 7 is a side view of fastener shown in Fig. 6.

30 Fig. 8 is an end view on edge of fastener shown in views 6 and 7.

Fig. 9 is a front view of the same fastener made double and adapted for attachment to vertical sections of the box.

35 Fig. 10 is a top view of double fastener shown in view 9.

Fig. 11 is a top view in section of the end member in line A B Fig. 3 showing vertical grooves adapted to hold the binding 40 bolts.

Fig. 12 side elevation of box showing binding bolts from top to bottom in assembled box.

The same numbers refer to similar parts 45 in the several views and descriptions in the singular number apply to a plurality of similar parts.

My invention consists of six separable members of which the top and bottom members are of similar construction. The opposite members of the sides are similar to each other, likewise the opposite end members are similar to each other.

50 Referring to numbers indicating construction details number 1 designates the walls of the top and bottom members, 2 their

transverse reinforcing bars, 3 the open ended vertical slots in the ends of said bars, 4 the slotted fastener shown in Figs. 6, 7 and 8 mounted in alinement with said vertical slots 3. The ends of the top and bottom wall members 1 are provided with underside retaining cleats 5 to hold the end members in position when the box is set up. Each side wall 6 is provided with horizontal 60 reinforcing bars 7 with groove 8 in alinement with slots 3. Each end wall 9 is provided with vertical reinforcing bars 10 shouldered to receive the ends of bars 7. The outer edge of reinforcing bar 10 is 70 grooved from end to end in alinement with vertical slot 3 and mounted fastener 4. The groove 12 in bar 10 is for mounting the binding bolt 13, when the box is set up and packed. The binding bolt 13 is provided 75 with locking washers 14 adapted to lodge behind the right angle flange 15 of the slotted fastener shown in Figs. 6, 7, 8, 9 and 10 and to lock the threaded binding bolt 13 when the nuts 16 mounted thereon is 80 tightened on the locking washer 14. The flange 17 of the slotted fastener shown in Figs. 6, 7 and 8 is made to turn over the edges at right angles of the transverse reinforcing bar 2, and attached thereto by suitable rivets.

The slotted fastener shown in Figs. 9 and 10 is essentially the same as shown in Figs. 6, 7, and 8. The fastener shown in Fig. 9 is provided with flange 15 at each end and 90 connected by continuous bar or other suitable means adapted for mounting in the cut out 11 of vertical bar 10. The said vertical fastener may however be an open slotted flanged fastener at one end and closed slot at the other so that it will carry binding bolt 13 at one end and detach it from the other when the box is collapsed. In large size boxes binding bolt 13 may be a continuous rod from top to bottom of box. 100

The locking washer 14 may be a punched piece of metal to fit loosely on the binding bolts and may be annular or rectangular in form and in thickness, equal or slightly exceed the height of flange 15 and be adapted to lodge behind it. In operation the binding bolts 13 are placed in the slots of the flanged fasteners mounted in alinement with the vertical slots on the transverse reinforcing bars and the locking washer 14 which is 105 loosely mounted on the binding bolt 13, lodged behind the flange 15. The nut 16 is 110

tightened on the threaded binding bolt 13, clamping the locking washer 14 behind the flange 15, thereby holding the binding bolt rigidly in position. To collapse the box the 5 nuts 16 are loosened enough to lift the locking washer 14 above flanges 15 thereby releasing the binding bolts 13 from the slotted fasteners. The transverse reinforcing bars 2 are mounted flush or over flush with the 10 ends of wall 1 and additional reinforcing bars may be spaced between the end bars. Bar 2 is made to extend beyond wall 1 and overlap the ends of bars 10 and 7. Bar 7 overlapping the shoulder of bar 10 at the 15 ends and to extend beyond the wall 6 equal to the distance of the thickness of wall 1. The edges of wall 6 thus become a supporting ledge for the edges of wall 1 and the horizontal bars 7 a protection to the edge of 20 wall 1. The horizontal bars 7 extend beyond the ends of wall 6 overlapping the vertical reinforcing bars 10 where shouldered, said shoulder being a right angle cutout equal to horizontal reinforcing bar in cross 25 section. This method of placing the reinforcing bars when set up and bound together in the manner described makes them equivalent to a reinforcing frame around the edge of each wall member.

30 I claim novel arrangement of the reinforcing bars, novel construction and joining of reinforcing bars, novel method of binding together and by reason of these features a box easy to make and use and 35 adapted as a shipping container for heavy material requiring large, strong packing cases.

What I claim and for which I desire Letters Patent is:

40 1. In a knockdown box, similar top and bottom members provided at each end with a transverse reinforcing bar having a vertical slot in each end; similar side members provided with upper and lower horizontal 45 bars having vertical grooves adjacent their

ends; similar end members provided with vertical reinforcing bars having grooves in their outer longitudinal faces and provided with shoulders; the slots of the first said bars and the grooves of the second said bars 50 alining with the grooves in the corresponding bars of the end members and the said shoulders engaging the said horizontal bars of the side members in the assembled box; binding bolts seated in said alined slots and 55 grooves and fasteners having flanged slots for retaining said bolts.

2. In a knockdown box, similar top and bottom members, provided at each end with a transverse reinforcing bar having a vertical slot in each end; similar side members provided with upper and lower horizontal reinforcing bars projecting beyond the walls of the side members and overlapping; in assembled box, the walls of the top and bottom members; said reinforcing bars of the side members extending at the ends beyond the walls of the side members overlapping in assembled box, the shouldered reinforcing bars of the end members; similar end members provided with vertical reinforcing bars shouldered and grooved in their outer longitudinal faces; the slots of the transverse reinforcing bars of the top and bottom members and the grooves of the reinforcing bars of the side members alining in the assembled box with the grooves of the reinforcing bars of the end members; binding bolts, provided with loose locking washers and nuts, seated in said alined grooves and 65 slots, and fasteners having flanged slots for retaining said bolts.

In testimony whereof I affix my signature in the presence of two subscribing witnesses.

GEORGE H. TOWNSEND.
